(57) **CLAIM**

The ornamental design for an exercise board, as shown and described.

DESCRIPTION

FIG. 1 is a front perspective view of an exercise board showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear perspective view thereof.

FIG. 9 is an enlarged view of the exercise board taken from the circle part in FIG. 1.

FIG. 10 is an enlarged view of the exercise board taken from the circle part in FIG. 3; and,

FIG. 11 is an enlarged view of the exercise board taken from the circle part in FIG. 6.

Broken lines in the drawings depict portions of the exercise board and form no part of the claimed design, and the dot-dash-dot lines depict the boundary of the enlarged views and form no part of the claimed design.
